UNITED STATES PATENT OFFICE.

WILLIAM R. EICHENSER, OF JOHNSTOWN, PENNSYLVANIA.

LUBRICATOR.

No. 854,636.

Specification of Letters Patent.

Patented May 21, 1907.

Application filed January 16, 1906. Serial No. 296,339.

To all whom it may concern:

Be it known that I, WILLIAM R. EICHENSER, a citizen of the United States of America, residing at Johnstown, in the county of Cambria and State of Pennsylvania, have invented certain new and useful Improvements in Lubricators, of which the following is such a full, clear, and exact description as will enable others skilled in the art to which it applies to make and use the same, reference being had to the accompanying drawings, forming a part hereof.

This invention relates to improvements in lubricators of the type shown in Letters-Patent No. 782,734 granted to me February 14, 1905, and it consists in certain novel features hereinafter first fully described and then particularly pointed out in the appended claims.

In the annexed drawings, which fully illustrate my invention, Figure 1 is a side elevation showing the device applied to the wrist-pin and cross-head of an engine; Fig. 2 is a longitudinal section of the lubricator, and Fig. 3 is a detail transverse section of the trough. Fig. 4 shows a modification.

In carrying out the present invention, I attach to the cross-head, directly over its journal, a short vertical pipe, A, to which, near the upper end of the same, is secured one end 30 of a conducting pipe, B. The opposite end of this pipe B communicates with the wrist-pin through a short vertical pipe, C, and a suitable coupling, as clearly shown and as will be readily understood. Within this pipe B, I fit a tube, D, provided at intervals with internal shoulders, E, arranged to arrest any backward flow of the lubricant. In the preferred form of the invention, these shoulders or stops are constructed by crimping or compressing the body of the tube so that on the side toward the wrist pin a face will be presented at a right angle to the axis of the tube while on the other side a tapered bore leading to a central opening in the said face will 45 be provided, as shown at F.

In the modified form shown in Fig. 4, the arresters consist of inclined plates, G, secured within the tube, the inclination being from the side of the tube toward the outlet or 50 wrist pin end of the same.

Secured to the upper end of the pipe A and to supports, H, I, erected upon the pipe B, is a trough or oil-receiver, J, which is provided in its bottom with openings, K, L, registering with the pipe A and with the support H, respectively, the said support H being hol-

low while the support I may be hollow or solid as may be most convenient. Between the openings K and L, I secure a transverse partition, M, in the trough and the upper edges of the side walls of the trough are provided with inwardly and downwardly projecting flanges, N, which extend to the medial line of the trough and have their inner edges arranged one above the other so as to present a small opening through which the oil may pass into the trough. When the parts are assembled, the partition M will be arranged directly over the cross-head and the portion of the trough extending toward the wrist pin will be about five times as long as the other portion, experience having shown that the wrist pin requires about five drops of oil to one drop for the cross-head. The oil or other lubricant is supplied from a cup, O, supported by a standard P on any convenient part of the frame of the engine, the cup being arranged at about the central point of the travel of the partition M.

The operation will be readily understood. The oil is permitted to escape from the oil cup at the speed best adapted for the successful and economical supply of lubricant to the bearings and drops therefrom into the oil receiver or trough whence it passes through the connecting pipes A and B to the bearings. The trough will be equal in length to the stroke of the engine so that oil will be caught therein in all positions of the pitman and the feed of the oil consequently be continuous. The receiver or trough forms a reservoir or source of constant supply of oil so that oil will be fed to the bearings even during the very short interval needed to replenish the main supply in the oil cup. The flanges on the inner sides of the walls of the trough effectually prevent oil splashing from the trough so that there will be no waste of oil. The oil-arresters in the tube D constitute pockets which catch the backwardly-flowing oil and thereby create a supply throughout the length of the said tube in order that oil will be maintained constantly close to the wrist pin and there will be no cessation of the lubrication caused by the travel of the oil along the pipe B.

It will be readily understood from the drawings considered in connection with the foregoing description, that the oil for the cross-head passes almost directly to the same while the oil for the wrist-pin is caused to flow thereto through the pipe B as the pin

descends while on the upward movement of the pin the oil will tend to flow backward. This backward movement is counteracted by the oil-arresters so that the oil be held toward the wrist pin.

5 My invention is not confined to the specific construction of the oil-arresters or conical check-valves and it would be within the scope of the invention to form them on the 10 inner wall of the pipe B. This construction, however, is very expensive and I prefer to form the checks on the tube D and then slide the tube into the pipe as the tube may be of cheap sheet metal and the desired rigidity 15 and strength will be furnished by the outer incasing pipe B. Should the necessity arise, the tube may be readily removed from the pipe and a new tube inserted without requiring the renewing or replacing of the more 20 costly outer pipe.

Having thus described my invention, what I claim and desire to secure by Letters-Patent is:—

1. In a lubricator of the character set 25 forth, the combination of a pipe rising from the cross-head, a pipe leading to the wrist pin, and a trough supported by said pipes, provided with openings in its bottom communicating with said pipes, and having a trans- 30 verse partition between said openings.

2. In a lubricator, the combination of oil- 35 conveying pipes, a trough supported by and communicating with the said pipes, and a partition within the trough between the points of communication with the said pipes,

there being flanges at the upper edges of the trough extending inward to the medial line thereof and having the edges out of contact.

3. In a lubricator, the combination of a trough, pipes supporting said trough and 40 communicating therewith and leading to the cross-head and wrist-pin respectively; and oil-arresters in the pipe leading to the wrist-pin.

4. A pipe mounted so as to reciprocate 45 with the pitman of an engine, and adapted to convey oil to the points of use, there being an opening in the upper side of said pipe, and check valves in said pipe adapted to prevent the return of oil to said opening. 50

5. A pipe mounted to reciprocate with the pitman of an engine and adapted to convey oil to the points of use, there being an opening in the upper side of said pipe, and conical checks in said pipe arranged to prevent the 55 return of oil to said opening.

6. A pipe mounted so as to reciprocate with the pitman of an engine and adapted to convey oil to the points of use, there being an opening in the upper side of the pipe, and 60 check-valves or oil-arresters removably fitted in said pipe and arranged to prevent the return of oil to the said opening.

In testimony whereof I have signed this specification in the presence of two subscr- 65 ing witnesses.

WILLIAM R. EICHENSER.
